DECORATED GLASS, MIRROR, AND THE
LIKE

Jack M. Powell, Cincinnati, Ohio

Application June 8, 1934, Serial No. 729,649

2 Claims.

(Cl. 41—22)

This invention relates to the decoration of glass panels, pieces, mirrors, and the like.

An object of the invention is to provide a process for applying a shaded design to the rear face 5 of a transparent panel which design, when viewed through the front face of the panel, has the same effect as designs which heretofore have been produced only upon the front face.

Another object is to provide a process for decorating mirrors in a novel and effective manner.

Another object is to provide panels, mirrors, and the like, having novel decorated effects produced thereon.

Another object is to provide a decorative panel of the class described and the process for producing the same which panel has the normal appearance and character of a mirror as viewed from the front, but which, when illuminated from the rear displays designs and other decorative effects applied thereon in a manner peculiar to this invention.

These and other objects are attained by the means and processes described herein and illustrated in the accompanying drawing, in which:

Fig. 1 is a front elevational view of a section of glass mirror.

Fig. 2 is an enlarged cross sectional view taken on the line 2—2 of Fig. 1.

Fig. 3 is a cross sectional view similar to Fig. 2 illustrating a modified form of the invention.

Heretofore the application of designs to the rear face of glass sheets, panels or the like has been effected by the use of flat colors only, the pleasing effects of shading on rear face applications of this kind never having been achieved. Shaded designs have, of course, been produced in the usual way upon the front surfaces of panels, windows, and other desired locations, but these designs were not satisfactory from an economic standpoint since they were constantly exposed to scratching and abrasion, and particularly in the case of window decoration, to the effects of weather conditions. The present invention contemplates the application of designs to the rear face of glass sheets, panels, and the like by the use of the air brush and of particular processes described herein whereby the designs applied have the same appearance, as viewed from the front, as the designs heretofore applied directly upon the front. It is obvious that inner surface designs of this kind are not subject to the various possible injuries to which the front face designs are constantly exposed.

The present invention likewise provides for a novel form of decorative panel, piece, or the like

which is particularly useful and desirable in connection with interior decorations such as panels for lamp shades and any number of various uses which readily suggest themselves. This modified form of the invention consists of a panel normally having the appearance of a mirror, as viewed from the front, but which, when illuminated from behind, displays colors and designs which have been applied, according to this invention, to the rear of the panel.

With reference to the drawing: a design may be applied, in accordance with the present invention, to the intended rear face 5 of a glass panel or the like, a section 6 of which is illustrated. The process is preferably carried out by the use of the air brush and stencils though it is apparent that other suitable media may be utilized. Initially, the color intended to form the shading of the completed design is applied in selected areas within the limits of the design. In the present instance, the shading is represented by the black areas 7. The color particles in each one of these areas are applied in progressively greater diffusion whereby an effective graduation of the shading is achieved in predetermined portions thereof. Thereafter, another desired color 8, such as orange, is applied over the previous color areas, said additional areas overlapping the initial color areas. In this way, the more thinly applied portions of the initial areas are modified by the superimposed area so that a graduation of color between the black and the orange is achieved. This graduation occurs at and adjacent the part indicated in Fig. 2 by the numeral 9. The areas 8 are likewise progressively more thinly applied in selected portions, as illustrated at 10. The design, in the present instance is illustrated as being completed by a final area of yellow indicated at 11. This color may be applied over the entire area of the design thereby serving as a backing.

It is to be understood that the design so applied represents a sufficient decoration for a clear glass panel, window, or the like. In the present instance the design is illustrated as applied to a mirror. Accordingly, the silvering 12 of the mirror is applied over all the rear surface of the panel 6 except that portion thereof covered by the design, the silvering being brought up to the edges of and totally embracing the design as indicated at 13. If the design is to be applied to a mirror which has already been silvered, the exact area of silvering requisite for a desired design, is cleared, and the design applied in the cleared space in the manner above described.

A very effective decorative panel may be formed in this way. A mirror to which a design has been applied in the manner described, may be positioned before a light so that the design is illuminated before a light so that the design is illuminated. The light rays illuminating the design, however, are precluded from passing through the glass at the edges of the design due to the fact that the design is positioned on the rear of the glass of the mirror and the silvering meets the edges of the design at all points. In other words, the design completely fills the area which is clear of silvering. Heretofore, designs have been applied in the usual way to the face of a mirror and an area of silvering, corresponding to the design, cleared away from the back of the mirror, but the light rays pass through the glass at the edges of the design, due to the thickness of the glass intervening between the edge of the cleared area and the edge of the design.

In Fig. 3 a modified form of the invention is illustrated. Herein, the glass sheet 14 is given an initial light coat of silvering 15 and the design 16 then applied over the silvering. A final protective transparent coating 17 such as clear varnish may be superimposed over the whole design. This design is applied in light coatings so that the panel will not be rendered opaque where it is covered by the design. It is obvious that the design need not necessarily be applied in the manner illustrated in connection with Figs. 1 and 2. However, as illustrated in Fig. 3, the design has been applied in the same manner as the design in Fig. 2 to produce the effective shaded portions which render a design much more attractive than the usual flat colors. It will be noted in Fig. 3 that the comparative thinness of the color areas of the design has been represented by the proportionately greater thickness of the glass 14.

When the panel thus formed is not illuminated, the silvering 15 gives the panel, as viewed from the front, the appearance and general character of a mirror, however, when the panel is illuminated from behind, the design is rendered visible. It will be apparent that the design or other decoration may cover the complete inner surface

of the panel rather than only a section of it as herein indicated. It has already been suggested that the invention illustrated in Fig. 3 is particularly effective for forming lamp panels, shadow lamps, chandelier sections, wall lights, illuminated advertising signs and devices, and in various other locations and uses which may suggest themselves.

What is claimed is:

1. The process of applying to the rear face of 10 transparent glass or the like a colored design adapted to be viewed through the front face of the glass and characterized by the smooth and gradual blending of colors and the appearance of depth in the completed design, said process 15 comprising first spraying onto said rear face an area of color intended to form the shading of the completed design, the color particles forming the shading being applied in progressively greater diffusion outwardly from a concentrated 20 mass whereby an effective graduation is achieved, and subsequently in the same manner spraying on an additional area of color or colors, each additional area overlapping the previous area 25 so that smooth blending is effected in the diffused portions of said previous area, the last color being applied over the whole design to serve as a visible portion thereof and likewise as a backing therefor.
2. The process of applying to the rear face of 30 transparent glass or the like a colored design adapted to be viewed through the front face of the glass and characterized by the smooth and gradual blending of colors and the appearance of depth in the completed design, said process 35 comprising first spraying onto said rear face an area of color intended to form the shading of the completed design, the color particles forming the shading being applied in progressively greater diffusion outwardly from a concentrated mass 40 whereby an effective graduation is achieved, and subsequently in the same manner spraying on an additional area of color or colors, each additional area overlapping the previous area so that smooth blending is effected in the diffused portions of said previous area.
